UNITED STATES PATENT OFFICE.

EMIL TYDEN, OF HASTINGS, MICHIGAN.

SEAL-LOCKED CAN.

1,076,616.

Specification of Letters Patent. Patented Oct. 21, 1913.

Application filed March 5, 1913. Serial No. 751,935.

To all whom it may concern:

Be it known that I, EMIL TYDEN, a citizen of the United States, residing at Hastings, in the county of Barry and State of Michigan, have invented new and useful Improvements in Seal-Locked Cans, of which the following is a specification, reference being had to the accompanying drawings, forming a part thereof.

10 The purpose of this invention is to provide an improved construction of a can or like article, comprising a body member and cover member, having provisions for locking them together at closed position with 15 the lock adapted to be secured by a seal.

It consists in the elements and features of construction shown and described as indicated in the claims.

In the drawings:—Figure 1 is a side elevation of a can equipped according to this invention. Fig. 2 is a section at the line, 2—2, on Fig. 1 on an enlarged scale. Fig. 3 is a detail section at the line, 3—3, on Fig. 2. Fig. 4 is a detail view similar to Fig. 25 3 showing a modification. Fig. 5 is a view similar to Fig. 3 showing another modification. Fig. 6 is a section at 6—6 on Fig. 5. Fig. 7 is a section at 7—7 on Fig. 5.

The drawings represent a can of the general character which will be recognized as a milk-shipping can comprising a body member, 1, and a cover member, 2, telescoped with the body, both being cylindrical at their telescoped position, the body member having its upper end portion, 3, flared outwardly and the cover member which extends up in cylindrical form to the top having its top extended forming a flange, 4, which overhangs the flaring upper end of the body member and is curved downward so as to extend outside of the periphery of said flared upper end of the body which is finished by an outwardly-turned wire bead, 5, which is engaged by an inwardly-turned wire bead, 6, of the cover flange at closed position of the can members, as seen in Fig. 1. For the purpose of this invention there is mounted upon the outer side of the body member, preferably in the angle between the cylindrical and the flared conical portion, and thereby partly upon the latter, a seal-locking device comprising a housing, 7, and a bolt, 8, mounted for sliding in the housing, and positioned for thrusting its inner end through the flared portion 3, of the body member which is apertured in line with the

bolt slide-way to permit the bolt to be thus thrust through it for engagement with the inner member, which in the form shown, is the cover member of the can. For such engagement the cover member is provided with an upwardly-facing shoulder, 10, preferably produced by sinking a circumferentially-extending groove or channel, 11, in the outer surface of said member which may be rolled in or otherwise formed by familiar methods of sheet metal working. The housing, 7, is cut away from side to side across the path of the bolt at 7^a, to expose and give access to the bolt for manipulating it for engagement or disengagement with the inner can member.

As illustrated, preferably the bolt, 8, is cylindrical and is provided with an annular boss, 8^a, which is stopped against the housing at the withdrawn position of the bolt and against the wall of the outer member of the can at the limit of its in-thrust for locking. The transverse apertures, 7^a, of the housing above mentioned, is preferably 75 made as a notch or recess in the inner edge of the housing before it is applied to the can, the can completing the encompassment of the aperture when the housing is mounted on the can. The bolt is introduced 80 into its seat before the housing is applied to the can, and the can body prevents it from escaping when the housing is mounted upon said body. The housing has a seal 85 aperture, 7^b, extending through from side to side across the bolt slideway near the outer end portion of said slideway, so that any customary form of flat sheet metal seal introduced through said seal aperture, after the bolt has been moved to locking position, blocks the said bolt slideway and prevents the bolt from being withdrawn until the seal has been first withdrawn. If preferred, instead of providing the housing 90 with the seal aperture, such seal aperture 95 may be made in the bolt and positioned to be exposed at the aperture, 7^b, for the introduction of the seal when the bolt is at locking position; (see Fig. 4.)

Because it is preferable or more convenient to mount the locking device, as shown, in position to have the bolt thrust through the flared portion of the can body for engagement with the interiorly-telescoped cover member; and because at this position, 100 in order to keep the housing within the minimum dimensions, preferably so that it

shall not protrude farther from the can than the overhang of the cover, the bolt is positioned so as to be thrust at right angles to the inclined or flaring upper end portion 5 of the body. It is preferable to form the engaging head of the bolt so that it may present its engaging surface at right angles to the withdrawing movement of the shoulder of the cover with which it is to engage, 10 since otherwise;—that is, if its engaging surface extended obliquely to said withdrawing movement,—it might be possible to wedge it out of engagement and so remove the cover without unlocking it. In 15 order to give this direct right-angle engagement, the bolt, thrust in in an inclined direction, as shown, has near its inner end an annular groove, 8^c, which in section radial to the bolt, is substantially right-angled in form so that the slope nearest the 20 end, which is the part which engages with the shoulder, 10, of the cover member, extends at such engagement horizontally,—that is, directly across the path of withdrawing movement of the cover;—and the 25 groove, 11, is formed in said cover member with its lower side which constitutes the shoulder, 10, in a plane substantially at right angles to the axis of the can or direction 30 of the withdrawing movement of the cover. When the bolt is thus formed, it will be seen that it could not be thrust into the groove unless if at the lowest closed position of the cover member, the shoulder, 35 10, were at the level of the lower side of the knob, 8^d, which results from forming the bolt in the manner described, because that knob at its full diameter must be able to pass the lower outer margin of the groove 40 in entering the latter. It is preferable, therefore, to form the groove described in the bolt so that at the full in-thrust position of the bolt and lowest position of the cover the said annular groove of the bolt 45 45 at the lower side of the latter stands entirely within the groove; and the periphery of the shoulder, 10, is touched by the bolt at a point on the latter a little back of said annular groove of the bolt, as seen in Fig. 50 3. With the parts thus constructed, it will be seen that any attempt to withdraw the cover without having released the bolt might possibly cause the outer periphery of the shoulder, 10, operating on the inclined 55 under surface of the bolt, to wedge the body member and cover member of the can apart at this point sufficiently to admit the said margin of the shoulder, 10, up into the right-angled annular groove of the bolt, the 60 cover being withdrawn to the extent of the vertical depth of said annular groove, which would be unobjectionable, since it would not amount to opening the can; but at this point the shoulder, 10, would abut squarely 65 against the inner shoulder of the knob made

at the point at which the latter extends horizontally, and further withdrawing movement of the cover would have no tendency to either crowd or wedge the bolt back, or the body and cover members of the 70 can apart.

In Fig. 5, there is shown a modification in which the lock is mounted wholly on the cylindrical and telescoped portion of the outer member and engages the cylindrical and 75 interiorly telescoped portion of the inner member. In this form, the engaging bolt member is in the form of a hook, 15, positioned vertically, pivoted at its lower end in the housing, and having at its upper end a hook lip, 15^a, projecting inward through an aperture in the wall of the outer member for engaging an upwardly facing shoulder, 16, formed on the inner member, preferably by rolling a circumferentially-extending 80 groove, 16^a, into the outer surface of said outer member. A flat spring, 15^b, is preferably provided mounted in the housing and operating on the hook bolt to retract its hook lip out of engagement with the inner 85 can member. The housing, 17, mounted, as stated, upon the cylindrical portion of the outer member of the can, has for so mounting it two pairs of parallel vertically-extending 90 flanges or feet, 17^a, which seat upon the vertical outer wall of said can member, leaving free vertical clearance between them from the aperture through which the lip, 15^a, protrudes for locking downward, so that 95 there is no opportunity for the accumulation 100 of dirt at or around the aperture which would not be readily flushed off in cleansing the can. In this vertical clearance space, 17^b, the hook bolt, 15, is located. In the housing, 105 there is formed a slide path, 18, for a flat seal, 19, which slide path opens back of the of the pivoted hook bolt, 15, and when the flat seal bolt, 19, is in position in this slide path, it extends into the 110 clearance space, 17^b, and presents an edge 115 or side in that space at position for holding the seal bolt in its locked position; that is, with its lip, 15^a, engaged with the shoulder, 16, of the inner can member. Transverse to the slide path of the seal, 19, 120 the housing has an aperture, 20, which extends entirely across or through said slide path of the seal, and the seal has a tongue, 19^b, which stands normally in the plane of the seal, but is adapted to be bent into the 125 aperture, 20, when the seal is in position in the slide path for retaining the hook bolt in its locked position. The tongue is adapted to break from the seal body upon being bent back to its normal position in the plane of 130 said seal body, as will be necessary in order to permit the seal to be withdrawn, and said seal can, of course, be withdrawn when the tongue thus breaks off from the seal body. The tongue is designedly of sufficient size

to receive an indentifying mark, as the letters, X, Y, Z, shown upon it in the drawings; and any unauthorized tampering with the device for the purpose of withdrawing 5 the seal to unlock the can will be disclosed by the absence of this tongue, which will be broken off by any attempt to put it in a position to permit the withdrawal of the seal.

10 I claim:—

1. In a can or the like which comprises a body member and a cover member which are telescoped with each other, the outer of said members being flared outwardly at the upper part, in combination with said members, a seal locking device comprising a bolt and a bolt housing, one of said parts having an aperture for receiving a seal to retain the bolt at locking position, said bolt being mounted for thrusting through said flared portion for locking, the interior member having exteriorly positioned means for engagement of said bolt.

2. In a can or the like having a body member and a cover member telescoping with each other, in combination with said members, a seal locking device comprising a bolt and a bolt housing mounted upon the outer side of the outer member, one of said parts being apertured for receiving a bolt-securing seal, the bolt being mounted for thrusting through the outer member for locking engagement with the inner member, the inner member having a circumferentially-extending upwardly-facing shoulder for such engagement.

3. In a can or the like comprising a body member and a cover member telescoping with each other, in combination with said members, a seal-locking device mounted upon the outer side of the outer member comprising a bolt and a bolt housing, one of said parts having an aperture for receiving the bolt-securing seal, the bolt being mounted for thrusting through the outer of said members for engaging the inner member, and the inner member having a circumferentially-extending groove for engagement of the bolt.

4. In a can or the like comprising a body member and a cover member which is telescoped thereinto, the body member being flared at its upper part, and the cover member having a flange which overhangs the

upper end of said flared portion of the body; a seal-locking device mounted upon the outer side of the body member at its said flared part, comprising a bolt and a bolt housing, one of said parts being adapted to receive a bolt-securing seal, the bolt extending through said flared portion for engagement with the cover member and being exteriorly exposed for manipulation in the housing.

5. In a can or the like, comprising a body member and a cover member which are telescoped with each other, the outer of said members being flared outwardly at the upper part, in combination with said members, a seal-locking device comprising a bolt and a bolt housing, one of said parts having an aperture for receiving a seal to retain the bolt in locking position, said bolt being mounted for thrusting through said flared portion for locking, the interior member having a circumferentially-extending upwardly-facing directly transverse shoulder, and the bolt having for engagement with such shoulder a knob-like head produced by a circumferential groove back of the end, of which the wall nearest said end is sloped at an angle to the axis of the bolt approximating the angle of slope of the flare of the body.

6. In a can or the like having a body member and a cover member telescoping with each other, in combination with said members, a seal locking device comprising a bolt housing mounted upon the outer side of said member, one of said parts being apertured for receiving a bolt-securing seal, the bolt being mounted for thrusting through the outer can member for locking engagement with the inner member, the inner member having exterior means for such engagement, the housing being cut away opposite and below the bolt entrance of the bolt member for affording free access to the parts for cleansing in the vicinity of said bolt entrance.

In testimony whereof, I have hereunto set my hand, at Chicago, Illinois, this 24th day of February, 1913.

EMIL TYDEN.
